SIGNAL TYPE TORQUE INDICATING
WRENCH

Mark Hattan, Dayton, Ohio

Application September 13, 1944, Serial No. 553,853

10 Claims. (Cl. 81—52.5)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to wrenches, and more particularly to wrenches for indicating predetermined torque stresses.

In my copending application Serial No. 544,128 there is disclosed a torque indicating wrench comprising a flexure element adapted to transmit torque stress from the body of the wrench to a work head and to flex in degree proportional to the degree of transmitted stress. In conjunction with the flexure element, use is made of a pair of contact elements adapted for relative motion and mutual engagement in response to motion of the wrench body in transmitting torque stress through the flexure member. Manual adjusting means are provided calibrated in torque units whereby the contact elements are given an initial relative spacing corresponding to a desired torque stress, prior to the transmission or torque through the flexure member by manual force exerted on the wrench body. Mutual engagement of said contact elements occurs responsive to a degree of flexure predetermined by the initial spacing, the structure being such that the degree of flexure prior to engagement of the contact elements is proportional to the initial spacing provided therebetween. Signal means are incorporated in the wrench responsive to the mutual engagement of said contact elements for the purpose of apprising the operator that the desired torque stress has been reached. It is the object of my present invention to provide an improved structure for accomplishing the functions hereinabove set forth by simplification of the adjusting means and other parts of the device as will be understood from the description which follows with reference to the appended drawings in which:

Fig. 1 shows a longitudinal cross section through the body of a wrench;

Fig. 2 is a section through 2—2 of Fig. 1; and
Fig. 3 is an exterior view of the wrench.

With reference to the figures of the drawing, a wrench is disclosed comprising a handle portion 1 and an elongated tubular shank 2 integrally formed therewith. Pivoted at 4 within shank 2 is a flexure element 6 having a free end 6a protruding into a stress applying member 8 secured within the shank 2 by a force fit or the equivalent. The flexure element 6 is adapted to have a work head 9 fixedly secured thereto in any suitable manner, for example, as by a work head

2

adapter 10. A contact element comprising a rod 12 is disposed within the flexure element 6 and secured therein adjacent the pivot 4 by means of a plug 13 of insulating material, it being understood that the outer end of contact rod 12 is firmly fixed in the plug 13 so that the contact rod 12 is axially supported within the flexure element 6 and spaced from the interior surface thereof. Contact rod 12 has a free end 12a disposed adjacent contact element 14 which is radially disposed relative shank 2 and guided for reciprocation by a perforation 8a in the stress applying member 8, and having a contact end 14a and a cam follower end 14b. The contact end 14a is adapted to engage the free end 12a of contact rod 12 upon movement of the body member 2 about the pivot 4 when a torque stress is being applied, as will hereinafter be described. A spring 16 is employed to bias the cam follower end 14b against the rise and fall cam surface 17 of a cam 18. The cam 18 is supported rotatably on the exterior of body member 2 by means of side flanges 19 and 20, the flange 20 being adapted to abut shoulder 22 of handle portion 1 and a collar 23 being provided secured by a force fit or the equivalent around body member 2 to abut flange 19 whereby cam 18 is retained in place on body member 2, but permitted rotative freedom. It will be understood that rotation of cam 18 effects reciprocation of contact element 14, thereby spacing contact end 14a from the free end 12a of contact rod 12 according to the point of engagement of cam end 14b with the rise and fall cam surface 17. A ratchet mechanism generally indicated by 25 is provided in collar 23 for coaction with recesses provided in flange 19 for the purpose of holding cam 18 fixed in any position to which it has been rotated. Cam 18 is exteriorly provided with indicia 27 for coaction with an index marker 28 on the body portion 1 for setting the wrench to give a signal at a desired torque stress, the indicia 27 being calibrated in torque units. Incorporated within handle 1 are a plurality of flashlight cells 30a and 30b retained therein by an end cap 31 acting through a spring 32 to maintain series contact between the cells and bias the cell 30a against the center terminal of a signal lamp 34 having the peripheral terminal thereof threadedly secured in a metallic ring 35. An insulating collar 36 supports the metallic ring 35 within the handle portion 1 and metallic ring 35 is connected by a light flexible wire 37 to the free end 12a of contact rod 12. Ports 40 in handle portion 1 are provided so

that the lighting of lamp 34 will be visible to the operator, and protective plugs 41 of suitable translucent material, either plastic or glass, are secured in ports 40 to keep dirt and moisture from having access to the interior of the wrench.

In operation, cam 18 is rotated until some desired indicia thereon is in alignment with the index marker 28 which serves to initially space contact end 14a of contact element 14 with reference to the free end 12a of contact rod 12 in accordance with whatever portion of cam surface 17 is in engagement with the cam follower end 14b, as determined by the setting of the indicia. If torque stress now be applied to the handle portion 1, the stress is transmitted through stress applying member 8 to the flexure member 6, and thence to the work head 9, causing flexure of flexure element 6 to a degree proportional to the stress applied to handle portion 1 and simultaneously, due to the pivotal action at 4 between handle portion 1 and flexure element 6, contact element 14 moves toward contact element 12 ultimately engaging contact end 14a with free end 12a. Upon engagement between the contact end 14a and the free end 12a, a series circuit is established starting at the positive center terminal of the battery 30a and going through the center terminal of the lamp 34, the peripheral terminal thereof, ring 35, wire 31, free end 12a of contact rod 12, contact end 14a of contact member 14, through handle 1 to cap 31, spring 32, and the negative casing terminal of cell 30b. Accordingly, lamp 34 will light, the illumination thereof being visible to the operator through ports 40 as hereinabove described. The structure is so arranged that the higher the torque desired, the greater will be the initial spacing between the contact elements, whereby a greater flexure of the flexure element 6 will be required to cause engagement between the contact elements, and a correspondingly greater torque force will be required to be exerted on handle portion 1 before lamp 34 is energized.

Accordingly, it will be seen that I have provided a simple wrench structure wherein torque stresses may be predetermined by an adjusting means comprising a minimum of moving elements and I claim as my invention:

1. In a torque indicating wrench, a body member comprising an elongated tubular shank, a tubular flexure member axially disposed in said shank and pivoted thereto adjacent the outer extremity thereof and being adapted for attachment to a work head exteriorly of said shank, a rotary cam supported for rotation at the inner end of said shank and having a rise and fall cam surface, a radially reciprocable cam follower, electrical contact elements adapted for variable relative initial spacing therebetween by reciprocation of said follower, said follower being associated with one of said contact elements, rotation of said cam being operative to reciprocate said follower, means in said tubular shank adapted to engage said flexure member to transmit torque stress from said body member to said work head and said flexure member being adapted to flex under said stress, one of said electrical contact elements being movable with said body member whereby said elements are adapted for relative motion to a point of mutual engagement operative to energize a signal, the degree of flexure of said flexure member prior to said engagement being proportional to the stress transmitted therethrough and to the initial spacing provided

between said contact elements by rotation of said cam.

2. In a torque indicating wrench, a body member and a flexure member, pivot means whereby said body member is pivoted to said flexure member, said flexure member having means thereon adapted for attachment to a work head, means carried by said body member adapted to engage said flexure member to transmit torque stress from said body member to said work head, contact means in said body member comprising variably spaceable contact elements, one of said contact elements being movable with said body member and another of said elements being secured to said flexure member adjacent said pivot means, motion of said body member in transmitting stress to said flexure member being operative to cause engagement of said contact elements for energizing a signal, and means providing adjustable initial spacing between said contact elements comprising a cam member having a cam surface, one of said contact elements comprising a contact end and a follower end adapted to engage said cam surface.
3. In a torque indicating wrench, a substantially hollow body member and a flexure member supported therein, said flexure member being adapted to transmit torque stress from said body member to a work head secured on said flexure member, a first contact element movable with said body member and supported in an aperture of a wall thereof, a second contact element supported in the interior of said body member and secured against motion relative to said work head, said contact elements being adapted to be initially spaced and to mutually engage to energize a signal in response to motion of said body member in transmitting stress to said flexure member, and means for initially spacing said contact elements comprising an adjustable cam supported on the exterior of said body member and having a rise and fall cam surface directed toward said second contact element and operative to move said first contact element relative to said second contact element in response to adjustment of said cam, whereby the torque stress transmitted through said flexure member prior to engagement of said contact elements is proportional to said initial spacing.
4. In a structure as set forth in claim 3, wherein said first contact element protrudes through the wall of said body member and is provided with an exteriorly disposed follower end for engagement with said cam, said cam being rotatably supported on the exterior of said body member.
5. In a structure as set forth in claim 3, wherein said first contact element protrudes through the wall of said body member and is provided with an exteriorly disposed follower for engagement with said cam, said cam being rotatably supported on the exterior of said body member and said first contact element comprising an integral substantially cylindrical member spring biased into engagement with said cam surface and adapted for sliding and reciprocal motion through the aperture of said wall responsive to adjustment of said cam.
6. In a structure as set forth in claim 3 wherein said first contact element protrudes through the wall of said body member and has an exterior end adapted for engagement with said cam, a stress applying member disposed within said body member and adapted to transmit torque stress from said body member to said flexure member and having an aperture in substantial registration with said cam.

tion with said body member aperture, said first contact element being supported within the aperture of said stress applying member and adapted for reciprocable motion therein, and a spring disposed about said contact element and arranged to abut against said stress applying member and the exterior end of said first contact element to maintain said first contact element in operative engagement with the rise and fall surface of said cam.

7. A torque indicating wrench comprising a body member, a flexure member movably mounted with respect to said body member and having a work head rigidly mounted on one end thereof, means on said body member engageable with said flexure member adjacent the other end thereof, said flexure member being adapted to transmit torque stress from said body member to said work head and to flex in proportion to the degree of transmitted stress, a pair of contact elements carried by the body member and flexure member respectively and adapted for mutual engagement by motion of said body member in flexing said flexure member, said mutual engagement being effective to operate a signal, said contact elements being adapted for variable initial spacing therebetween whereby the degree of flexing of said flexure member prior to engagement of said contact elements is proportional to said initial spacing, and means for adjusting said initial spacing comprising a rotary cam radially disposed about said body member, one of said contact elements having a contact end adapted to be adjusted toward said other contact element by engagement of a portion of said one contact element with said rotary cam and upon rotation of said cam in one direction.

8. A torque indicating wrench as set forth in claim 7, wherein said cam comprises a rise and fall surface arcuately encompassing said one contact element, said one contact element comprising a member having a follower end adapted to engage said cam surface and having a contact end adapted for reciprocable movement relative to said other contact element upon actuation of said follower end by said cam, for varying the initial spacing between said contact elements, and spring means carried on said one contact element to provide for continuous engagement between said follower end and said rise and fall cam surface.

9. A torque indicating wrench comprising a hollow body member, a flexure member movably mounted in said body member and engageable

by means in said body member to transmit torque stress from said body member to a work head connected to said flexure member, a pair of contact elements within said body member, one being carried by said body member and the other being movably mounted in said body member and actuated by a portion of said flexure member, means responsive to mutual engagement of said contact elements to energize a signal, said contact elements being adapted for variable initial spacing therebetween whereby the degree of flexing of said flexure member prior to engagement of said contact elements is proportional to said initial spacing, means for adjusting said initial spacing comprising a cam having a rise and fall cam surface arcuately disposed about one of said contact elements and radially disposed about said body member, said one contact element being adapted for reciprocable movement relative to said other contact element and having a follower end operative by rotary motion of said cam to effect reciprocation of said one contact element, and means providing engagement between said follower end and said rise and fall cam surface.

10. In a torque indicating wrench as set forth in claim 9, wherein said body member comprises an elongated tubular shank and a handle portion, said cam comprising a ring-like member having side flanges and a rise and fall surface peripherally disposed internally therein, said cam being adapted to be rotatably supported by said side flanges on said tubular shank, said follower end of said one contact element being disposed between said flanges, a perforation in said tubular shank through which said contact element extends toward said other contact element and a stress applying member disposed between said body member and said flexure member and adapted to transmit torque stress therebetween.
